US00D763240S

(12) **United States Design Patent**
Amit et al.

(10) **Patent No.:** **US D763,240 S**
(45) **Date of Patent:** ** Aug. 9, 2016

(54) **PORTION OF A HANDHELD DEVICE**

(71) Applicant: **Google Inc.**, Mountain View, CA (US)

(72) Inventors: **Gadi Amit**, San Mateo, CA (US); **Daniel J. Clifton**, San Francisco, CA (US); **Paul Eremenko**, Sunnyvale, CA (US); **Inbal Etgar**, San Francisco, CA (US); **Susan Elizabeth McKinney**, San Francisco, CA (US)

(73) Assignee: **Google Inc.**, Mountain View, CA (US)

(**) Term: **14 Years**

(21) Appl. No.: **29/495,449**

(22) Filed: **Jul. 1, 2014**

(51) LOC (10) Cl. **14-02**

(52) U.S. Cl.

USPC **D14/250**; D14/341

(58) **Field of Classification Search**

USPC ..... D14/341, 496, 138 AA, 138 R, 138 C, D14/383, 250, 218; 345/173; 455/575.1

CPC H04M 1/00; B65D 85/00

See application file for complete search history.

(57) **CLAIM**

The ornamental design for a portion of a handheld device, substantially as shown and described.

DESCRIPTION

FIG. 1 is a perspective front view of a first embodiment of a handheld device.

FIG. 2 is a front view of the embodiment of FIG. 1.

FIG. 3 is a rear view of the embodiment of FIG. 1.

FIG. 4 is a left side view of the embodiment of FIG. 1.

FIG. 5 is a right side view of the embodiment of FIG. 1.

FIG. 6 is a bottom view of the embodiment of FIG. 1.

FIG. 7 is a top view of the embodiment of FIG. 1.

FIG. 8 is a perspective front view of a second embodiment of a handheld device.

FIG. 9 is a front view of the embodiment of FIG. 8.

FIG. 10 is a rear view of the embodiment of FIG. 8.

FIG. 11 is a left side view of the embodiment of FIG. 8.

FIG. 12 is a right side view of the embodiment of FIG. 8.

FIG. 13 is a bottom view of the embodiment of FIG. 8; and,

FIG. 14 is a top view of the embodiment of FIG. 8.

The claimed design, bordered by a dot-dash line in the perspective and rear views, is a portion of a handheld electronic device, such as a mobile telephone or tablet.

The broken lines in each figure illustrate graphical environmental features that form no part of the claimed design.

1 Claim, 8 Drawing Sheets

US D763,240 S
